MATCH PACKAGE AND METHOD OF
MANUFACTURING SAME

Paul Wilhelm Dietmann, Jonkoping, Sweden

Application September 9, 1931, Serial No. 561,951,
and in Sweden September 27, 1930

12 Claims. (Cl. 93—2)

This invention relates to match packages of the kind in which one or more rows of individual matches are connected as by gluing or pasting to a common base or envelope of cardboard, paper or the like. In packages of this kind it has been heretofore proposed to attach matches of cardboard to an envelope by pasting them along one edge thereof, the matches being adapted, when withdrawn, to be detached at the connecting point. It has proved, however, that the matches are generally held fast to the envelope with such a strength that they will break at the point where they are gripped rather than separate at the connecting point.

15 This invention has for its object to provide an improved match package of the above said kind and an improved method of manufacturing such packages in a simple and economical manner. According to the invention the matches are connected by gluing or pasting to tongues projecting from the envelope and formed integral therewith, said tongues being adapted to be torn off from the envelope when the matches are drawn out. Such a package is very suitable for 20 insertion in cigarette boxes or the like and in such case a striking surface may be provided in such manner as to ignite the match when withdrawn. The matches may be positioned close to each other or at slight intervals, preferably corresponding to the width of one match, in order to facilitate the gripping of the matches.

In the manufacture of such match packages a match strip and an envelope strip are preferably first manufactured separately. The 25 match strip may be manufactured by splitting a ribbon of suitable material at one or both edges so that the splints thus produced will be connected to a common base strip, whereupon the matches are impregnated with paraffine and 30 have heads put on. In order to provide spaces between the individual matches several match strips may, however, be cut from a ribbon of material in such manner that the matches of adjacent strips will engage the space between 35 each other alternately. The matches are thus only cut to part of their desired length which is of great advantage, as far as the heading of the matches is concerned, because the production of double heads will be prevented, which is a 40 usual drawback in connection with the heading of long and weak matches. The strip of material to be used as an envelope is first passed between rollers to provide it with a surface of striking material and is then passed, after drying, between pasting rollers, the match strip being then

carried to the pasted envelope strip. The strips are thereupon carried to a cutting tool by which the individual matches are separated, whereupon the envelope may be folded, if desired, around the headed ends of the matches and the strips may be cut to the desired lengths.

60 The invention is illustrated in two examples in the accompanying drawing, in which Fig. 1 illustrates two successive stages of the manufacture of a package according to the invention, while Fig. 2 shows the finished package and Fig. 3 illustrates a somewhat modified method of manufacturing.

With reference to the drawing, the numeral 1 indicates a strip of paper, cardboard or other 70 suitable material at the edges of which two rows of oppositely positioned matches 2 are partially cut. The distance between the matches of each row is equal to the width of the matches, inasmuch as, for the sake of saving of material, the cutting operation has been effected in such manner, which is well-known per se, that a similar match strip the matches of which engage the spaces between the matches 2 will be obtained at each edge of the strip 1. The undivided central portion of the match strip is attached by 75 gluing or pasting to the centre of a ribbon of material 3 which is adapted to be used then as an envelope for the matches and which is provided with striking surfaces 4, 4' prior to the attaching of the matches and, if desired, 80 also with prints. After drying of the glue or paste that portion of the match strip 1 which is situated between each pair of opposite match spaces together with the corresponding portion 85 of the envelope ribbon 3 is removed by a cutting operation. The match strip 1 as well as the ribbon 3 of material are previously provided with 90 perforations 5 intermediate between each pair of opposite matches to permit correct conveyance of the strip and ribbon so that the said cutting away operation will divide the envelope material 3 in two halves, one for each row of matches, and will further make the matches completely free 95 from each other so that the matches will only be connected to the respective tongues 6 of the envelope, see Fig. 2, to which they are attached by gluing and which have been formed by the 100 said first-mentioned cutting operation. By 105 transverse slits packages 7 of suitable length are then cut off. Prior to this cutting operation the envelope ribbon 3 has been provided with longitudinally extending folding scorings 8 to permit the packages to be easily folded to 110

their final form, shown in Fig. 2, prior to or subsequent to the cutting operation.

In the embodiment shown in Fig. 1 the distance between the matches of each row is made larger than normal at uniform intervals corresponding to the desired width of the packages in order that the envelope may obtain the desired width with relation to the row of matches included therein. This arrangement, however, is not absolutely necessary.

The envelope is formed from a material which allows the tongues which serve to attach the matches to the envelope to be torn off at their base without requiring the envelope to be held or compressed with such a power that the matches will be torn off at the same time. In certain cases it may be of advantage to weaken the tongues at their base, which may be effected, for instance, by making incisions in well-known way at the base of the tongues or by moistening the envelope ribbon along the base of the tongues with a liquid capable of weakening the fibres of the material.

Instead of entirely removing the material situated between opposite match spaces the matches may also be separated by cutting this material in such a way that laps which only hang together with the envelope will remain between the tongues, said laps being of approximately the same length and the same width as the tongues. Said laps may then be folded to engage the envelope between the matches to serve as guide-ways for the matches. It is to be noted that said tongues should, preferably, be somewhat narrower than the match space in order to permit the match heads to pass therebetween or, the heads should have a width which must not be greater than that of the matches. Because of the fact that the laps are naturally thicker than the matches, an undue pressure cannot be exerted upon the matches, in the withdrawal thereof from the envelope. In case the laps be attached by gluing to both sides of the envelope they will form, together with said sides, passages which are closed all around and which are of a less depth than the thickness of the match heads so that upon the withdrawal of the matches the heads will be pressed, due to the elasticity of the material, against the striking surfaces with a sufficient pressure to cause ignition without requiring any compression of the envelope by hand. Instead of pasting the laps to both sides of the envelope the necessary pressure may also be secured by placing a metal clip around the envelope at the level of the laps which clip will maintain the sides of the envelope in engagement with the laps.

In Fig. 3 a modified method of manufacturing the package is illustrated. Also in this case there is pasted to the envelope ribbon 3 a match strip 1 having two rows of oppositely directed matches 2 and which is produced in the same way as described with connection to the match strip shown in Fig. 1. The matches of both match rows, however, are not situated in register with each other but are displaced relatively to each other by a distance which corresponds to the width of the matches. The separation of the matches or the envelope halves is effected in this case by a zigzag-shaped cutting 9 formed in the central portion of the match strip and the envelope. It is seen that there is no loss of material at all in this case. It should be noted that the package may also contain two rows of matches, provided both of the opposite marginal

portions of the envelope are formed with tongues, and have matches attached thereto so as to render the packages symmetrical with respect to the line 8 of Figs. 1 and 3.

What I claim is:—

1. A match package, comprising in combination a row of matches and a common envelope of sheet material having tongues projecting therefrom and formed integrally therewith, the matches being pasted to said tongues. 80

2. A match package, comprising a plurality of matches, a common envelope of sheet material having integral tongues projecting therefrom, matches pasted to said tongues, and a striking surface on said envelope so located as to cause the match heads to rub thereagainst in the withdrawal of the matches from the package. 85

3. A match package, comprising a plurality of matches, a common envelope of sheet material having integral tongues projecting therefrom, matches pasted to said tongues, said envelope being folded around the headed ends of the matches, and a striking surface on said envelope at each side of the matches. 90

4. A match package, comprising a plurality of matches, a common envelope of sheet material having integral tongues projecting therefrom, matches pasted to said tongues, said tongues being separated by spaces corresponding to the width of the matches, and a striking surface or 100 surfaces on said envelope so located as to cause the match heads to rub thereagainst in the withdrawal of the matches from the package. 105

5. A match package comprising a plurality of matches, a common envelope of sheet material 110 having integral tongues projecting therefrom, matches pasted to said tongues and integral laps between the individual tongues, said laps being folded down on the envelope between the individual matches so as to form guide-ways between themselves for the 115 matches.

6. A match package, comprising a plurality of matches, a common envelope of sheet material having integral tongues projecting therefrom, matches pasted to said tongues and integral laps 120 between the individual tongues, said laps being of a width substantially corresponding to that of the matches and being folded down on the envelope between the individual matches so as to form guide-ways between themselves for the 125 matches.

7. A method of manufacturing match packages which comprises producing a strip of matches coherent to a common portion, pasting said common portion to a ribbon of sheet material, and separating the individual matches from each other by subjecting the material of the match strip and the ribbon to a cutting operation. 130

8. A method of manufacturing match packages which consists in producing a strip of matches coherent to a common portion, pasting said common portion to a ribbon of sheet material, separating the individual matches from each other by subjecting the material of the match strip and the ribbon to a cutting operation, folding said ribbon so as to inclose the match heads, and securing the opposite portions of the ribbon to form an envelope for the matches. 135

9. A method of manufacturing match packages which consists in producing a match strip comprising two rows of oppositely directed matches coherent to a common portion, pasting said common portion to the central portion of a ribbon of sheet material, separating the individual 150

- matches from each other by a cutting operation giving as result two separate packages strips, folding and securing the ribbons of each such strip to form an envelope for the respective 5 matches.
10. A method of manufacturing match packages which consists in producing a match strip comprising two rows of oppositely directed matches coherent to a common portion, cutting 10 a material of sheet material to the shape of a ribbon, applying striking surface mass to said ribbon, pasting said common portion of the match strip to the central portion of said ribbon, separating the individual matches from each 15 other by a cutting operation giving as result two separate packages strips, folding and securing the ribbons of each such strip to form an envelope for the respective matches.
11. A method of manufacturing match packages which consists in producing a match strip comprising two rows of oppositely directed matches coherent to a common portion, adjacent matches of each row being separated by spaces corresponding to the width of one match and 20 positioned in register with the spaces of the other row, pasting said common portion to the 25
- central portion of a ribbon of sheet material, separating the individual matches from each other by a zigzag-shaped cut formed in said common portion so as to form two separate package strips, folding and securing the ribbons of each such strip so as to form an envelope for the respective matches. 80
12. A method of manufacturing match packages which consists in producing a match strip comprising two rows of oppositely directed 85 matches coherent to a common portion, adjacent matches of each row being separated by spaces corresponding to the width of one match and positioned in register with the spaces of the other row, cutting a sheet material to form a 90 ribbon, applying striking surface mass to said ribbon, pasting the common portion of the match strip to the central portion of said ribbon, separating the individual matches from each other by a zigzag-shaped cut formed in said 95 common portion so as to form two separate package strips, folding and securing the ribbons of each such strip so as to form an envelope for the respective matches. 100
